United States Patent Office

Des. 196,234
Patented Sept. 10, 1963

196,234

ARMCHAIR

Jerry Johnson, 3739 S. Rodeo Drive, Malibu, Calif.

Filed Apr. 25, 1963, Ser. No. 74,617

Term of patent 7 years

(Cl. D15—1)

FIG. 1 is a front perspective view of an arm chair showing my design,

FIG. 2 is a rear perspective view, and

FIG. 3 is a rear elevational view thereof.

The side not shown is like the other side shown.

I claim:

The ornamental design for an armchair, as shown and described.
